DISCHARGE APPARATUS FOR PUMPS

Louis H. Pierce, Mankato, Minn.

Application November 9, 1940, Serial No. 365,089

2 Claims. (Cl. 103—179)

My invention relates to underground discharge apparatus for pumps.

The principal object of the invention is to provide efficient, simply constructed apparatus which may be readily installed in any well casing to discharge water from the well underground into a storage tank or the like.

To the accomplishment of the above, and subordinate objects presently appearing, the preferred embodiment of my invention has been illustrated in the accompanying drawing, set forth in detail in the succeeding description, and defined in the claims appended hereto.

In said drawing:

Figure 1 is a view partly in vertical section and partly in side elevation of the preferred embodiment of my invention installed,

Figure 2 is a view in transverse section taken on the line 2—2 of Figure 1, and

Figure 3 is a similar view taken on the line 3—3 of Figure 1.

Referring to the drawing by numerals, according to my invention, a lower section 1 of the usual well tubing, of suitable length, arising from the conventional underground pump cylinder 2 has threaded on the upper end thereof a short upstanding coupling sleeve 3 provided above said section 1 with a lateral, central, discharge port 4 therein and a radial top flange 5. Fitting around the coupling sleeve 3, below the flange 5, is a bushing 6, threaded thereon, said bushing fitting in and being secured to the lower end of the well casing 7 by cap screws 8. A lateral, underground discharge pipe line 9 is threaded through the lower end of the casing 7 and through the bushing 6 into communication with the discharge port 4.

The upper end of the well casing 7 is closed by an annular cap piece 10 undercut, as at 11, to fit into said end and suitably secured thereto.

An upper section 12 of well tubing is threaded into the cap piece 10 to depend for a suitable distance therefrom into the casing 7. A short section 13 of brass well tubing is threaded at its lower end into the top of the coupling sleeve 3 and connected to the lower end of the section 12 by a sleeve coupling 14 threaded onto said sections 13 and 12. Set screws 15 extending radially into the flange 5 of coupling sleeve 3 flush with said flange additionally secure the section 13 in said coupling sleeve 3.

The sucker rod 16 of the pump extends out of the lower section 1 up into the coupling sleeve 3 and is connected by a short sleeve coupling 17 to a sucker rod section 18 extending downwardly

through the upper section 12 into the section 13, said rod section 18 being equipped in the section 13 with a pump piston 19 of the inverted cup type adapted to exert pressure downwardly under the down stroke of said rod sections.

A vertical, through drain port 20 extends through the coupling sleeve 3 at one side thereof.

The upper section 12 is provided therein, within the casing 1, with a lateral back pressure relief port 21.

As will be understood, the sucker rod 16 is provided in the pump cylinder 2 with the usual pump piston, not shown.

The operation of the described invention will be readily understood. The water is pumped from the pump cylinder 2 up into the coupling sleeve 3, and tubing section 13, under the upstroke of the sucker rod 16, and the rod section 18, and by the pump piston in said cylinder and forced out of said sleeve and tubing section by way of the discharge port 4 and pipe line 9 under the down stroke of said rod section 18 and piston 19. Back pressure against the piston 19 is relieved through port 21 and port 20 and any water leaking past the piston 19 into the upper tubing section 12 drains out of the latter by way of said port 21 into casing 7 and out of the latter by way of port 20.

By turning the sections 12, 13, and sleeve 3 in the proper direction the sleeve may be unscrewed from the bushing 6 and section 1 so that said sections 12, 13 and the sleeve 3 may be pulled out of the casing 7 as a unit, and the cap piece 10 removed therewith so that the sucker rod line may be pulled and access to the pump cylinder 2 for repair or replacement had, all without digging up or disconnecting the discharge line 9.

The foregoing will, it is believed, suffice to impart a clear understanding of my invention without further explanation.

Manifestly the invention as described, is susceptible of modification without departing from the inventive concept and right is herein reserved to such modifications as fall within the scope of the subjoined claims.

What I claim is:

1. The combination with a pump cylinder to be sunk in a well, a tubing section extending upwardly from said cylinder, and a sucker rod extending from said cylinder upwardly from said tubing section, of a well casing surrounding said rod and tubing section and extending above the same, a lateral discharge line tapped into said casing immediately above said tubing section

and adapted to be buried in the ground, a sleeve member secured in said casing and to said tubing section for detachment therefrom and removal upwardly through said casing and provided with a lateral discharge port therein communicating with said discharge line, a tubing line arising from said sleeve member and removable therewith, and a sucker rod section in said tubing line coupled to the first mentioned sucker rod for detachment therefrom and provided with a downwardly acting piston operating in said tubing line above said coupling sleeve.

2. The combination with a pump cylinder to be sunk in a well, a tubing section extending upwardly from said cylinder, and a sucker rod extending from said cylinder upwardly from said tubing section, of a well casing surrounding said rod and tubing section and extending above

the same, a lateral discharge line tapped into said casing immediately above said tubing section and adapted to be buried in the ground, a sleeve member secured in said casing and to said tubing section for detachment therefrom and removal upwardly through said casing and provided with a lateral discharge port therein communicating with said discharge line, a tubing line arising from said sleeve member and removable therewith, and a sucker rod section in said tubing line coupled to the first mentioned sucker rod for detachment therefrom and provided with a downwardly acting piston operating in said tubing line above said coupling sleeve, said tubing line being provided above said piston with a lateral back pressure relief vent therein leading into said casing.

LOUIS H. PIERCE.
